Des. 929

J. H. Ransom, of Albany, N. Y.
Letters Patent No. 929. Dated Aug. 25, 1857.

The schedule referred to in these Letters Patent, and making part of the same.

Be it known, that I, Samuel H. Ransom, of the city of Albany, State of New York, have produced a new and original ornamental design for the plates of a stove; called by me the Northern Light Stove, and I declare the annexed delineations, forming part of this specification, an accurate representation of the said plates, which are combined to form the said Stove, with their ornamented parts; the left front door, the right side and doors and the oven rear plate not represented being symmetrically similar to the right front door, the left side and door, and the oven front plate which are represented.

What I claim as my production and design to secure by Letters Patent, is the combination and arrangement of ornamental figures and forms represented in the accompanying delineations, forming together the ornamental design for the plates of a Stove.
